J. A. KLESLER

PLUMB BOB

Original Filed Oct. 10, 1919

Fig. III

Fig. II

Joseph A. Klesler
Inventor:
By *Joseph A. Klesler*,
Atty

UNITED STATES PATENT OFFICE.

JOSEPH A. KLESLER, OF PORTLAND, OREGON.

PLUMB BOB.

Application filed October 10, 1919, Serial No. 329,733. Renewed October 18, 1922. Serial No. 595,448.

To all whom it may concern:

Be it known that I, JOSEPH A. KLESLER, a citizen of the United States of America, and resident of city of Portland, in the county of Multnomah, in the State of Oregon, have invented certain new and useful Improvements in Plumb Bobs, of which the following is a specification, reference being had to the accompanying drawing.

10 My invention relates to plumb bobs and has for its object the production of improvements in the device described by me in U. S. Letters Patent No. 1,286,023, dated November 26, 1918.

15 The improvement contemplated in my present invention is to provide means for locking the suspension cord to my plumb bob at any length thereof desired, and independently of the mechanism by which, as in 20 my patent aforesaid, the cord is wound into the cavity of the plumb bob.

What constitutes my present invention will be hereinafter specified in detail and succinctly set forth in the appended claims.

25 In the accompanying drawing,

Figure I is a longitudinal central section of the detachable frame of my device which comprises the working parts thereof, and which, when assembled within the plumb 30 bob proper, shown in Figure III, constitutes the complete device as shown in the last named figure.

Figure II is a transverse section on the line II—II of Figure I.

35 Figure III is a side elevation of my device in present preferred form of embodiment, shown as depending, as in use, from its suspension cord.

40 Referring to the numerals on the drawing, 1 indicates a plumb bob proper, which may be of any preferred weight, dimensions and exterior contour. It is provided in its upper end with a preferably cylindrical cavity into which is threaded, as by aid of 45 screw threads 3, a frame comprising a cap 5 and a pair of legs 6.

The legs 6 accommodate between them a rotatable drum 7, as upon an arbor 8.

50 The drum is provided preferably at one end with a gear 10 which meshes with a spur-gear 11 that is revoluble upon a stud-shaft 12.

55 The gear 11 is secured, as by pins 14, to a beveled gear 15 that meshes with a beveled gear 16. The gear 16 is coaxially threaded or otherwise secured to a tubular

shaft 17 that is provided, on its outer end, with a preferably integral actuating-head 18, that is pierced by a continuation of the bore of the shaft 17.

Between the gear 16 and the cap 5 is interposed an expansive coiled spring 19 which is preferably let into a cavity 20 provided for it in the inner face of the cap 5 and its neck from which the legs 6 project. 65 The function of the spring 19 is to compel normal engagement between the beveled gears 16 and 15 through thrust imparted to the gear 16 and shaft 17 to which said gear is secured, and at the same time to keep 70 the head 18 pressed against a disk collar 21 surrounding the shaft 17 and interposed between the head 18 and the outer face of the cap 5.

75 The elements above specified exemplify cord reeling mechanism, and are, in effect, with slight or immaterial variations, indicated in the drawing, the same as those shown and described in my Letters Patent aforesaid, and being described therein in detail do not require further explanation in my present application to which their relation is only incidental.

Coming now to specification of my present invention, 25 indicates a tubular extension projecting coaxially from the head 18, with which it is preferably integral. The bottom 26 of its bore is of truncated conical shape whose dimensions are such as to crowd the three balls 27 with which it is provided, towards its axis, into gripping engagement with the suspension cord 28, somewhat after the manner of and to the same effect as a pin vise. A plunger 29, headed to fit the bore of the extension 25, functions to urge the balls 27 into cooperation as specified under the force of a coiled spring 30 introduced between the head of the plunger 29 and the cap 31 threaded within the enlarged end of the bore of the extension 25. The 100 plunger itself extends through the cap 31 and is provided with a coaxial bore 32 through which the suspension cord 28 of the plumb bob is fed between the balls 27.

105 The number of the balls 27 is preferably three, because that number functionates well, but a greater number could be used if desired.

110 The operation of my plumb bob is substantially the same as that described in my patent aforesaid.

In my present device, when the cord 28 is

paid out or taken in to a desired length, the cap 31 is screwed down so that the balls 27 are caused to engage the cord 28 and hold it. As often as it is desired to run the cord free into or out of the plumb bob, the cap 31 may be loosened sufficiently to release the balls 27 and to permit the cord 28 to slip freely through the space between them; but always a pull of sufficient force upon the cord 28 10 against the power of the spring 30 will draw it out, despite the fact that the spring 30 be strong enough to sustain the weight of the plumb bob without slipping.

15 The presence of the extension 25 interferes in no wise with the operation of the means of disengagement between the gears 15 and 16, provided for by the pins 35 in the head 18 which find accommodation ordinarily in sockets 36 in the disk collar 21.

20 What I claim is:

1. In a plumb bob having cord reeling means, a cap having an aperture centrally through its top, a head, a shaft on said head extending through said aperture, a tubular 25 extension on said head opposite to the shaft, the bottom of said tubular portion being tapered inwardly, means adapted to close the outer end of said extension, there being aligned bores through said shaft and closing 30 means, balls seated in the tapered portion of said tubular extension, and means comprising

ing a spring and plunger adapted to cooperate with said tapered portion and closing means to urge said balls inwardly whereby to grip a bob-supporting line passed through 35 said bores.

2. In a plumb bob having cord reeling means, a cap having an aperture centrally through its top, a head, a shaft on said head extending through said aperture, a tubular 40 extension on said head opposite to the shaft, the bottom of said tubular portion being tapered inwardly, means adapted to close the outer end of said extension, there being aligned bores through said shaft and closing 45 means, balls seated in the tapered portion of said tubular extension, and means comprising a spring and plunger adapted to cooperate with said tapered portion, closing means to urge said balls inwardly whereby 50 to grip a bob-supporting line passing through said bores, and means for regulating the force of the spring which actuates said plunger.

55 In testimony whereof, I have hereunto set my hand in the presence of two subscribing witnesses.

JOSEPH A. KLESLER.

Witnesses:

JOSEPH L. ATKINS,
JOHN B. CLELAND.
